J. A. DAVIDSON

SLITTER AND PERFORATOR FOR CYLINDER AND KELLY PRESSES

Filed Dec. 26, 1924

INVENTOR
John A. Davidson
BY C. P. Goepel
ATTORNEY

UNITED STATES PATENT OFFICE.

JOHN A. DAVIDSON, OF BROOKLYN, NEW YORK.

SLITTER AND PERFORATOR FOR CYLINDER AND KELLY PRESSES.

Application filed December 26, 1924. Serial No. 758,041.

To all whom it may concern:

Be it known that I, JOHN A. DAVIDSON, a citizen of the United States, and a resident of Glendale, Brooklyn, in the county of Queens and State of New York, have invented certain new and useful Improvements in Slitters and Perforators for Cylinder and Kelly Presses, of which the following is a specification.

10 This invention relates to slitters and perforators for cylinder and Kelly presses and has for its object to provide an improved device to overcome the disadvantageous features of those devices of a similar nature 15 now in use.

Heretofore, such slitters or perforators were provided, but they had the disadvantage that the paper to be slit or perforated could not be controlled causing an imperfect 20 register, and the control of the slitting or perforation could not be had, and more over they necessitated the use of a steel band for perforation as a backing underneath the tympan on the cylinder which was disadvantageous in use.

25 My improved invention comprises a slitter or perforator which, by virtue of its position in respect to the roll, provides a very sharp cut and can be readily controlled. It 30 is simple in structure and facile in its use.

The invention will be hereinafter disclosed in connection with the embodiment shown in the drawings, and the said invention will be described and finally pointed out 35 in the claims.

In the accompanying drawings—

Figure 1 is a side view of a cylinder press arranged in respect to its type carriage and showing the positioning of my improved device 40 vice in respect to these parts;

Fig. 2 is a plan view of the end of my improved device;

Fig. 3 is a vertical side view;

Fig. 4 is a vertical side view of a different 45 side to that shown in Fig. 3, and

Fig. 5 is a plan view of a perforating wheel.

Similar characters of reference indicate 50 corresponding parts throughout the various views.

Referring to the drawings, and more particularly to Figs. 2 to 5, my improved device consists of a standard 10 having a split joint bearing member 11 at one end thereof on 55 which is seated a clamping portion 12 held

to the bearing member 11 by screws 13 adapted to be fastened in position by the thumb members 14. The bearing member 11 and the cap member 12 are adapted to be clamped by these screws 13 tightly against a support 15 which is held on a bracket 16 suitably supported on the stationary bed 17, as shown in Fig. 1, though this support 15 may be secured to the frame of the cylinder press in any other suitable manner.

The other end of the standard 10 is provided with a forked member consisting of legs 18 and 19 which support a shaft 20 suitably held in position by a device 21 of well known construction. Interposed between the legs 18 and 19 the slitting wheel 22 is supported on the shaft 20 in any suitable manner. The shaft 20 is provided with bearing members or washers 23 interposed between the slitter or perforator 22 and the legs 18 and 19 so as to keep the slitter or perforator 22 in suitable position and the shaft is also provided with an end washer or cap 24 arranged along one of the legs 18 or 19 of Fig. 3, this cap 24 being arranged along the leg 19 of Fig. 3. The perforator may be provided with projecting teeth 25 as shown in Fig. 5 with an opening 26 through which the shaft passes, or in the event of a plain slitter being used the knife edge along the peripheral portion is a single continuous cutting edge. The configuration of the teeth 25 may be of any suitable shape as is well known in the art.

The device as has been described supported on the support 15 in turn supported by a suitable bracket 16 is so arranged in respect to the cylinder that it enters into the bite of the cylinder 30 and the printing type 31, which printing type 31 is supported on the movable member 32 which reciprocates to and fro as is well known. The slitter or perforator portion of the device is arranged as far inwardly into the bite between the cylinder 30 and the type 31 as is practical so as not to contact with the type but to contact with the paper held on the cylinder. This paper 33 is held at one end 34 and after the paper is printed and slit or perforated it is released and a new sheet of paper is applied all in a manner well known. The improvement upon a cylinder press to adapt it to my improved device consists in providing a tympan upon the cylinder and providing this tympan with

gaps. I have indicated the tympan by 36 and the gaps by 37. When then the slitter or perforator 22 presses against the paper and this in turn presses against the tympan 5 a slitting or perforating action upon the paper on the cylinder 30 results, but when the perforator or slitter 22 passes over the paper in juxtaposition to the gaps 37 the lack of resistance prevents a sufficient 10 tenacity, and hence the paper is not cut or slitted.

Thus, it will be seen that my invention resides in providing a perforator or slitter in the bite of a cylinder and type as closely 15 as permissible so as to keep in registration and to bring the perforator or slitter as near to the best printing surface as possible, and at the same time provide the tympan with 20 gaps so as to prevent the slitting or perforating at certain parts of the paper as desired.

My invention is particularly applicable to the simultaneous printing and slitting or perforating of check books or the like, and the simplicity of parts gives efficiency to the 25 structures and the arrangement of the perforator or slitter as close as possible to the best printing surface gives a very efficient cut or perforation.

I have thus described my invention by the 30 use of an embodiment thereof as shown in the drawings and described in the specification, but I do not wish to be limited to details thereon as it is clear that changes may be made therein without departing from the 35 spirit and scope of the invention as defined in the appended claims.

I claim:

1. The combination with a cylinder printing press, including a rotary cylinder and a 40 movable bed, a perforator or slitter mounted with its cutting edge in close relation to the

printing surface and cooperating therewith in its cutting operation.

2. The combination with a cylinder printing press including a rotary cylinder, and 45 a movable bed, of a perforator or slitter mounted with its cutting edge in the bite of the cylinder or printing surface as near to the printing position as possible and cooperating with the cylinder or printing surface 50 in its cutting operation.

3. The combination with a cylinder printing press including a rotary cylinder, a stationary support, and a movable printing bed carried by said support, of a perforator or 55 slitter carried by said stationary support adapted to have its cutting edge cooperate with the rotary cylinder.

4. The combination with a cylinder printing press including a rotary cylinder, a stationary support and a movable printing bed carried by said support, of a perforator or 60 slitter carried by said stationary support in close relation to the printing surface along the cylinder, and a tympan surrounding the 65 cylinder adapted to cooperate with the cutting edge of said perforator or slitter.

5. The combination with a cylinder printing press including a rotary cylinder, a stationary support and a movable printing bed 70 carried by said support, of a perforator or slitter carried by said stationary support in close relation to the printing surface along the cylinder, and a tympan having gaps 75 therein, surrounding the cylinder adapted to cooperate with said perforator or slitter for cutting paper carried on the cylinder except in parts where the gaps in the tympan occur.

In testimony that I claim the foregoing as my invention, I have signed my name hereto.

JOHN A. DAVIDSON.
